US0D1064009S

(12) **United States Design Patent** (10) **Patent No.:** **US D1,064,009 S**
(45) **Date of Patent:** **** Feb. 25, 2025**

(54) **BURR CUTTER**

(71) Applicant: **SUGINO MACHINE LIMITED**,
Toyama Prefecture (JP)

(72) Inventors: **Masahide Yamazaki**, Uozu (JP);
Mitsuru Muto, Uozu (JP)

(73) Assignee: **SUGINO MACHINE LIMITED**,
Namerikawa (JP)

(**) Term: **15 Years**

(21) Appl. No.: **35/518,069**

(22) Filed: **Aug. 17, 2022**

(80) **Hague Agreement Data**

Int. Filing Date: **Aug. 17, 2022**

Int. Reg. No.: **DM/223022**

Int. Reg. Date: **Aug. 17, 2022**

Int. Reg. Pub. Date: **Aug. 18, 2023**

(57) **CLAIM**

The ornamental design for a burr cutter as shown and described.

DESCRIPTION

1. Burr cutter

1.1: Perspective

1.2: Front

1.3: Back

1.4: Top

1.5: Bottom

1.6: Left

1.7: Right

1.8: Cross sectional

Figure 1.8, is a cross-sectional view taken along the A-A line shown in Figure 1.2. The broken lines in the reproductions depict portions of the burr cutter that form no part of the claimed design.

1 Claim, 8 Drawing Sheets
